UNITED STATES PATENT OFFICE

2,463,685

AUTOMATIC FREQUENCY CONTROL
SYSTEMGordon L. Fredendall and Alfred C. Schroeder,
Feasterville, Pa., assignors to Radio Corpora-
tion of America, a corporation of Delaware

Application July 31, 1944, Serial No. 547,355

2 Claims. (Cl. 315—29)

1

The present invention relates to automatic frequency control or phase control circuits and particularly to novel apparatus for the synchronization of cathode ray deflecting circuits in television receivers or the like.

In some locations, generally near the edges of the service area of a television station, local interference or weak signals, or perhaps both, impair the accuracy of synchronization in a television receiver to such an extent that the horizontal resolution is appreciably reduced. There may also be failure of interlace and even sporadic failure of synchronization. This invention aims to provide an improvement in synchronizing action that will improve performance in these marginal locations without introducing compromising factors. For signal conditions which are at all satisfactory for reception, substantially the maximum horizontal resolution permitted by the television channel may be realized in a receiver embodying the present invention when allowance is made for unavoidable noise effects seen in the image as beam modulation. Also, noise effects do not destroy interlacing or cause "tearing" of the picture in horizontal strips. Appreciable improvements in vertical synchronization is also obtained.

In accordance with this invention, these and other desirable results are attained by providing improvements in previously prepared television receiving equipment in which synchronization of an oscillator is to be obtained by employing an automatic frequency control circuit responsive to any change in the time relationship of the synchronizing pulses with respect to saw-tooth wave used to control or provide deflection.

A further object of the invention is to provide an improved method of and means for synchronizing the deflecting circuit or circuits of an image producing device.

A further object of the invention is to provide an improved television synchronizing circuit that is less affected by noise in the incoming signal than previously known devices.

A still further object of the invention is to provide an improved television receiver.

In accordance with the invention, a phase detector compares the relative phase of the incoming synchronizing pulses and the saw-tooth deflection wave and generates a signal which varies in accordance with the phase.

Other and more specific objects of the invention will become apparent and suggest themselves to those skilled in the art to which the invention

2

is directed upon reading the following specification and claims in connection with the accompanying drawings in which:

Fig. 1 is a schematic representation of a portion of a television receiver embodying the invention;

Figs. 2a to 2d are curves illustrating the operation of the schematic circuit of Fig. 1;

Fig. 3 is a circuit diagram of substantially the entire deflecting arrangement of a television receiver embodying a development of Fig. 1; and

Fig. 4 is a modification of the receiver circuits of Fig. 3.

Referring for the present to Fig. 1 of the drawings, which illustrates the invention in simplified form, a phase detector 10 is fed with sync pulses applied to the primary 12 of a transformer 14 by way of the terminals 16. These sync pulses are separated in any known manner from the video signal in the sync separating circuits of a television receiver of which the apparatus of Fig. 1 forms a part. It will be understood that in the discussion which is to follow, these sync signals will be either horizontal or vertical sync pulses, the disclosure of Fig. 1 being applicable to either. The phase detector is also fed with a saw-tooth wave of voltage from a scanning oscillator 17 over a connection 18, this saw-tooth voltage wave being the same as or similar to a wave fed to the deflection coils or deflection plates of the image producing device (not shown) over a connection 19. The saw-tooth wave is applied at the midpoint of the secondary 21 of the transformer 14 so that it is applied in phase to condensers 24 and 26. The condenser 24 serves to couple the end 28 of the secondary to the anode of a diode 29, the other end of the secondary 29 being coupled through the transformer 26 to the cathode of a diode 31. The cathode of the diode 29 is connected to the anode of the diode 31, this connection serving as the output terminal, indicated by reference character 32, of the phase detector 10. The D. C. return paths for the diodes 29 and 31 are provided by resistors 34 and 36 respectively, having a common terminal which is grounded as shown, thereby providing a balanced arrangement for the phase detector 10.

The diodes 29 and 31 function as peak detectors by selecting appropriate values for the resistors 34 and 36. The discharge paths of the condensers 24 and 26 have a relatively long time constant.

The point 32 is physically connected by a conductor 39 to the grid of a D. C. amplifier 41 com-

prising the tube 42. A filter 43, having an impedance characteristic such that inappreciable saw-tooth voltage appears at the grid of the amplifier 42, is connected between the point 32 and ground. The filter is indicated as comprising a pair of branched circuits, but inasmuch as design methods for providing a suitable filter are well known to those skilled in the art, no detailed description of the design or operation of the filter will be given. The output of the amplifier tube 41 is D. C. coupled to the scanning oscillator in accordance with the signal impressed across the amplifier 42. An analogous operation with respect to a blocking oscillator is described in Patent No. 2,344,810, granted to these applicants on March 21, 1944.

The operation of the arrangement of Fig. 1 with synchronizing pulses derived, for example, from the sync separating circuits of an associated television receiver and impressed on the primary 12 of the transformer 14 will be described. In the secondary 21, sync signals of opposite polarity with respect to ground are super-imposed on a saw-tooth wave derived from a source such as either the horizontal or vertical deflection circuits, for example, of the associated television receiver. It may be assumed for purposes of description that the horizontal deflection circuit is represented in Fig. 1 by the device designated previously by the reference character 17. The signals on condensers 24 and 26, shown in Figs. 2a and 2b, correspond to one assumed condition of phasing of the saw-tooth voltage and the sync pulses. The saw-tooth voltages e_{24} and e_{26} at these points are of the same polarity, whereas the voltage pulses e_s and e_{s1} are of opposite polarity. Any change in the phase relationship of the saw-tooth wave and sync pulses will cause an increase in the peak amplitude of one composite signal and a decrease in the peak amplitude of the other. In order to simplify the drawing, the voltage pulses e_s and e_{s1} are not shown as differentiated pulses, only the portion of the pulses that is effective being shown.

Across the resistors 34 and 36, that is to say on the diode side of the condensers, the voltages are those shown in Fig. 2c. These voltages include the D. C. voltage inserted by the peak rectifier action of the diodes 29 and 31. The peaks of the sync pulses are held at the same reference level, this level being indicated as zero for the given example.

The signal appearing at the point 32 is shown in Fig. 2d, and it will be seen that the sync pulses have been balanced out, leaving a signal containing only the saw-tooth wave components. The saw-tooth component of the signal shown in Fig. 2d is filtered out by the filter 43, and a D. C. control potential is obtained which is not a fluctuating saw-tooth wave but is a very slowly varying signal when noise is present.

This control potential is amplified by the amplifier tube 41, which has in its plate circuit the usual plate load resistor 44 and such other equipment as may incidentally be included in the scanning oscillator or deflection source 16. In the case illustrated, the average potential existing between the waves in Fig. 2c at the instants when the sync pulses occur is zero. If a small phase displacement occurs between sync pulses and the saw-tooth wave, the peaks of sync continue to be maintained at zero potential, but the average potential at point 32 is lowered or raised, depending on whether the pulse moves to an advanced or to a retarded position in time relative to the saw-

tooth wave. The feedback action is such that the change in speed of the oscillator tends to reduce the magnitude of the phase discrepancy between a saw-tooth cycle and a pulse that gave rise to the increment in the control voltage.

The equilibrium position of the pulses is a function of the settings of the speed control but is constrained to lie somewhere on the return time of the saw-tooth. A speed control is usually 10 to be found in apparatus of the type designated by reference character 16. When the amplitude of noise is sufficiently great, some noise peaks tend to be held at zero potential by the action of the diodes 29 and 31. The potential at the point 15 32 tends to fluctuate about zero, if the distribution of the noise is random. Under such circumstances, the D. C. component is zero. It is important here to note that the wave forms of noise and saw-tooth do not appear at the junction of the diodes as disturbing components of the control voltage. Variations in the difference between the "instantaneous A. C. axes" of the two saw-tooth waves would appear at point 32 in the absence of the filter 43. The function of the filter 20 is the removal of the higher frequency components of this control voltage and the transmission of only the very low frequency components. In the absence of noise, the latter are a true indication 25 that a readjustment in the phase of the oscillator is necessary for the maintenance of accurate synchronization. Low frequency components 30 are indications of a drift in circuit constants or small changes in the frequency of the transmitted sync pulses.

Referring to Fig. 3 of the drawings, certain 35 parts of a typical television receiver modified to incorporate features of this invention are shown diagrammatically. The video amplifier, D. C. restorer, synchronizing separator, and the deflection 40 generators are shown.

A tube 51 serves as a video amplifier, the video 45 signals from the second detector of the receiver (not shown) being impressed on the control grid 53 of this tube by way of a connection 54. The output circuit of the tube 51 includes a peaking 50 arrangement indicated generally by reference character 55. Inasmuch as this arrangement has been employed in previously known television receivers, its functions and operation will not be described in detail. The output to the image producing device, such as a "Kinescope," is indicated at 58. Usually, this connection will effectively terminate at the control grid of the Kinescope. A tube 59 of the duplex type serves as a D. C. 55 restorer and also as a sync pulse separator amplifier. The cathode 61 and the grid 62 together with the cathode resistor 63 serve as a diode rectifier with its load resistor to perform the function of a D. C. inserter since the control grid circuit of the image producing device is coupled through the resistor 63. The control grid 62 also causes the signals applied over a conductor 66 from the peaking circuits 55 to be repeated by way of a condenser 68 and applied to the control grid 69 of the tube 59. The grid and cathode elements 61 and 62 rectify the peaks of the synchronizing pulses which are applied to the cathode with negative polarity, and only the sync signals, therefore, are passed by the condenser 68 to the grid 69.

The pulses appearing on the grid 69 are present in the plate circuit of the plate 71 which includes a transformer 74 for passing horizontal sync pulses only and a transformer 76 having its primary 78 and its secondary 79 shunted by con-

densers 81 and 82 respectively for passing the vertical sync pulses only.

The horizontal deflection circuit of the image producing device is fed in the usual manner from the secondary 84 of a transformer 86. A horizontal saw-tooth generator including a tube 88 applies a saw-tooth voltage to a high impedance horizontal output tube 89. The plate circuit of this tube 89 is coupled to the horizontal deflecting means of the image producing device through the previously mentioned transformer 86.

The details of the horizontal saw-tooth generator 87 and the function and operation of the horizontal phase control 92 will now be described. The latter is similar to the phase detector and amplifier shown in simplified form in Fig. 1 of the drawings, and the broad features of the control function, exercised by the horizontal phase control, have been described previously in connection with Fig. 1. The cathode 94 and anode 96 of the duplex type tube 88 are elements of the usual blocking oscillator tube. The blocking oscillator includes, in addition, a feedback transformer 97, a condenser 99, which is charged and discharged, and a speed control resistor 102 which is in series with a resistor 103.

The blocking oscillator section of the tube 88 operates to produce pulses and is controlled in a manner to be described from the phase control 92. The elements 106 and 108 of the tube 88 serve as a discharge tube to generate a saw-tooth of voltage by charging and discharging a condenser 109. The resistor 111 serves as a width control. The saw-tooth voltage across the condenser 109 is applied through a condenser 112 to the grid 114 of the high impedance horizontal output tube 89. The plate circuit of this tube includes the primary 116 of the transformer 86 which also serves as a coupling impedance for applying the horizontal saw-tooth voltage to the secondary 118 of the previously mentioned transformer 14 by way of a conductor 119. A low pass filter composed of a resistor 121 and a condenser 122 produces a wave which is more nearly of saw-tooth form than the wave form of the output of the tube 89, which is of such character that saw-tooth current is produced in the horizontal deflecting coil of the Kinescope. The condensers 124 and 126 correspond to the condensers 24 and 26 respectively of Fig. 1. The duplex diode 123 corresponds to the diodes 29 and 31 of Fig. 1. Resistors 127 and 128 correspond to the resistors 34 and 36 respectively of Fig. 1. The filter constituted by the components 131, 132, and 133, corresponds to the filter 39 of Fig. 1, and 134 is a D. C. amplifier tube similar to the amplifier tube 42 of Fig. 1.

The filter-resistor 133 has a critical value, for each receiver of a given design in which it is used. When this resistor is too large, the sides of the image become scalloped; and when it is too small, the image as a whole vibrates in the horizontal direction. There is an intermediate range of values for which the image is correct.

The output of the D. C. amplifier 134 is applied to the grid 136 of the blocking oscillator triode section of the tube 88. This output is in the form of a signal which slowly varies when noise is present. The variation in this signal is added to or subtracted from the potential normally applied to the grid 136, this normal potential being variable at will within chosen limits by the speed control resistor 102. The manner in which the signal passed along by the amplifier 134 is varied has

been discussed above in connection with Fig. 1 of the drawings.

The vertical deflection circuits and vertical deflection control on Fig. 3 of the drawings are similar to and operate in the manner already discussed in connection with the horizontal deflection circuits. The adjustable resistor 139 serves as a height control and corresponds to the width control 111. The adjustable resistor 141 serves as a speed control and corresponds in function to the adjustable resistor 102. The adjustable resistor 142 serves as a vertical linearity control. A condenser 144 is charged and discharged to provide the voltage wave which, in conjunction with the input circuit constants of a tube 146 and a transformer 148, serves to drive a saw-tooth wave of current through the vertical deflecting coil (not shown).

It is desirable in the operation of an automatic frequency controlled television receiver to maintain a reasonably constant plate voltage supply for both sections of this tube 134, and the tube 88 and also its counterpart in the vertical deflection circuit when the gain control of the I. F. amplifier (not shown) is varied. An effective arrangement for insuring a constant plate voltage is disclosed in an application of G. L. Fredendall, Serial No. 526,287, filed March 13, 1944, now Patent Number 2,454,150, issued November 16, 1948.

Fig. 4 of the drawings shows a modification of Figs. 1 and 3 in which a transitron oscillator is substituted for the blocking oscillator and discharge tube shown by way of example in Fig. 3 of the drawings. Only a portion of a vertical deflecting circuit is shown by Fig. 4; and now with reference thereto, 160 corresponds to transformer 14 of Fig. 1 of the drawings. The separated vertical sync pulses are sync pulses which may further be separated by the aid of the transformer 160 and appear in the primary 162. The secondary 163 of the transformer may be center tapped or may be shunted by a resistor 164, as shown, which provides a point of connection for feedback over a conductor 168 of a saw-tooth wave originating in the oscillator represented in its entirety by reference character 168. The transitron oscillator is described in the "Proceedings of the Institute of Radio Engineers," October 1935, by E. W. Horold. The output of the AFC phase detector 170, which includes the diodes 171 and 172, appears at a point 174 which corresponds electrically to the point 32 of Fig. 1. The output of the phase detector 170 is applied to the No. 1 grid 176 of the tube 178 which is of the pentode type commonly used as a transitron oscillator. The plate circuit of this tube, which is connected to a source of positive potential, includes a resistor 181. A condenser 182 is connected to the plate of the tube 178 and to the cathode return circuit by a connection to the cathode 183 of a sync output tube 184. The condenser 182 is charged through the resistors 181 and 194 in operation of the oscillator. The No. 2 grid 186 of the tube 178 is connected to a source of positive potential through a resistor 188, and the No. 3 grid 189 is connected to ground through an adjustable resistor 191. A cathode resistor 190 provides a negative bias for the No. 3 grid 189. The grids 186 and 189 are coupled by a condenser 192. The duration of the saw-tooth pulse is controlled by the value of the resistor 191 and the resistor 181 in conjunction with a resistor 194. Assuming that the No. 3 grid 189 is positive and the anode is drawing current, the anode current is then considerably larger than the charging current

through the resistor 181. The condenser 182 is discharged rapidly. When the anode current is cut off, the grid 189 is driven negative, and this condition remains while the condenser 182 charges, the anode potential increases, and a point is reached at which the anode commences to draw current which normally would pass to the No. 2 grid 186. The potential on the No. 3 grid 189 again rises, since the grid 189 and the grid 186 are coupled, until the anode suddenly takes a large current, thus discharging the condenser 182. The charge and discharge characteristic of the condenser 182 is in the form of a saw-tooth of voltage which is coupled to the grid 198 of the tube 184 through a coupling condenser 199.

A portion of the output of the tube 184 is applied to the phase detector 170 by way of the previously mentioned feedback paths 166. A filter 203 serves to smooth the wave, which appears in the output of the tube 184, before it is applied to the phase detector 170. Thus, small deviations of the saw-tooth frequency and phase relative to the incoming sync pulses are detected by the diodes 171 and 172, and the result of this detection is passed on as a slowly varying control voltage to the oscillator 178. The action of this control voltage tends to restore the synchronism of the oscillator.

The cathode circuit of the tube 184 is connected illustratively in the manner shown for the cathode of the tube 146 of Fig. 3. The illustrative example in Fig. 4 of the drawings, therefore, is especially adapted for use as a vertical deflection circuit. However, it will be understood that the principles of operation explained above in connection with Fig. 4 of the drawings may be applied in a like manner to a horizontal deflection circuit.

Various alterations may be made in the present invention without departing from the spirit and scope thereof, and it is desired that any and all such alterations be considered within the purview of the present invention as defined by the hereinafter appended claims.

Having now described the invention, what is claimed and desired to be secured by Letters Patent is the following:

1. In an automatic frequency control arrangement for a television receiver, a transitron oscil-

lator having a connection for the control of generated frequency, a peak detector, a direct connection from said detector to said oscillator control connection, a deflecting circuit, an output connection from said oscillator to said deflecting circuit, a connection from said deflecting circuit to said detector to provide a wave to said detector having a beam deflecting characteristic, and means for applying synchronizing pulses to said detector, said pulses being divided and applied with opposite polarity to said detector and said wave being divided and being applied with like polarity to said detector.

2. In an automatic frequency control arrangement for a television receiver, a transitron oscillator comprising an electron tube having a control grid, a peak detector, a control connection from said detector to said transitron oscillator control grid, a deflecting circuit, an output connection from said oscillator to said deflecting circuit, a connection from said deflecting circuit to said detector to provide a wave to said detector having a deflecting characteristic, and means for applying sync pulses to said detector, said pulses being divided and applied with opposite polarity to said detector, and said wave being divided and being applied with like polarity to said detector.
